LAMP BASE

Norman Bennett, 9900 E. Bexhill Drive,
Kensington, Md.

Filed Oct. 12, 1965, Ser. No. 87,447

Term of patent 14 years

(Cl. D48—20)

instant invention;

The dominant features of my design reside in the portions shown in full lines.

I claim:

The ornamental design for a lamp base, as shown and described.
